14 Claims 10

ABSTRACT OF THE DISCLOSURE

A racemic or optically active, 4,6-dichloro-4,6-estradiene of the formula

(I)

wherein R is hydrogen, alkyl, tetrahydropyranyl or an acid residue.

To form the compounds, the 4-unsubstituted 6-chloro-estradiene is subjected to the action of an agent furnishing positive and negative chlorine, thereby forming the 6,6,7-trichloro-substituted compound, followed by treatment of the latter compound with a base.

The compounds have a very high progesterone activity.

BACKGROUND OF THE INVENTION

Compounds having a progesterone action and used therefore for treatment of gynecological afflictions have already been subjected to chlorination in the 4-position. However, the previous investigations showed that the chlorination in the 4-position resulted in a serious reduction of the effective action, see Canadian Journal of Chemistry, 37, p. 1785 (1959) and Chemistry and Industry, 14, p. 548 (1963).

It is therefore an object of the present invention to provide for gynecologically useful compounds which have a greatly increased progesterone activity.

SUMMARY OF THE INVENTION

The compounds of the invention are racemic or optically active 4,6-dichloro-4,6-estradienes of the formula

(I)

wherein R is hydrogen, alkyl, tetrahydropyranyl or an acid residue.

2

The invention also embraces a process for making these compounds by subjecting a 6-chloro-4,6-estradiene of the formula

(II)

5 wherein R has the same meaning as given above, to the action of an agent adapted to furnish positive and negative chlorine, thereby forming the 6,6,7-trichloro compound and then treating the trichloro compound with a base.

10 The invention also includes pharmaceutical compositions in which the defined compounds are the active agents.

15 The invention furthermore includes a process of treatment of gynecological afflictions by applying the pharmaceutical compositions just mentioned to a patient requiring such treatment.

DESCRIPTION OF THE PREFERRED EMBODIMENTS

If R is an acid residue, it may be formed by any physiologically compatible and acceptable acids. Preferred acids are carboxylic acids having up to 15 carbon atoms. The carboxylic acids can also be unsaturated, branched, 20 polyhydroxyl or can be substituted in conventional manner, for instance by hydroxyl or amino groups or halogen atoms. Suitable also are cycloaliphatic, aromatic, mixed aromatic-aliphatic or heterocyclic acids which likewise may be substituted in conventional manner. Examples of suitable acids are for instance the following: 25 acetic acid, propionic acid, butyric acid, valeric acid, caproic acid, enanthic acid, undecylic acid, trimethylacetic acid, diethylacetic acid, t-butylacetic acid, phenylacetic acid, cyclopentylpropionic acid, oleic acid, lactic acid, 30 mono-, di- and trichloroacetic acid, aminoacetic acid, succinic acid, adipic acid, benzoic acid, nicotinic acid. The conventional inorganic acids such as sulfuric and phosphoric acid may also be used.

35 Alkyl preferably is methyl, ethyl, propyl or butyl.

UTILITY

The 4,6-dichloro-4,6-estradienes of the invention have a surprisingly high progesterone action. In view of the literature above cited, this could not be expected.

40 The main application of the pharmaceutical compositions containing the compounds of the invention as the effective agent is in the treatment of the following gynecological afflictions: primary amenorrhea and secondary amenorrhea of extended duration, cycle irregularities in 45 case of inadequate function of the corpus luteum, endometriosis, uterine hypoplasia, premenstrual complaints, mastopathy, etc.

45 The dosage depends on the severity of the illness. Generally, it is advisable to administer between 5 and 100 mg. 50 of effective agent per day. Serious menstruation irregularities can for instance be corrected by a cycle corresponding treatment with daily doses of 10 mg. of effective agent. In the case of certain indications such as dysfunctional bleeding or medically advised anticonceptive treatment, the 55 compounds of the invention may also be administered in combination with an estrogenic component such as ethinyl estradiol.

Pharmaceutical compositions including the effective agents may be prepared in conventional manner, for instance by incorporating the compounds of the invention together with the conventional additives as used in galenic pharmacy, carrier materials and flavoring agents in any desired application form such as tablets, lozenges, capsules, pills, suspensions or solutions.

The concentration of effective agents in all these various types of pharmaceutical compositions depends on the kind of administration. For instance, an orally administered tablet should preferably contain 0.1 to 10 mg. of effective agent. A solution for parenteral application should preferably contain from 1 to 20 mg./ml. of solution. The parenteral application includes all possible types of administration such as subcutaneous, intramuscular and intravenous administration.

Tablets may for instance have the following composition:

	Mg.
4,6 - dichloro - 17 β - acetoxy - 18 - methyl - 17 α - ethinyl-4,6-estradiene - 3 - one, micronized (particle size 2-8 μ , occasionally up to 16 μ)	5.000
Lactose (DAB 6)	24.000
Corn starch (U.S.P. 16)	45.065
Talcum (DAB 6)	4.000
Gelatin, white (DAB 6)	1.400
Sodium laurylsulfate (USPQ 16)	0.500
p-Oxybenzoic acid ethylester (DAB 6, 3. Suppl.)	0.024
p-Oxybenzoic acid propylester (DAB 6, 3. Suppl.)	0.011
	80.000

PROCESS OF MAKING THE COMPOUNDS OF THE INVENTION

Both racemic (rac.) and optically active (nat.) 4,6-dichloro-4,6-estraidenes of the above given formula (I) may be formed, for instance, as follows:

The starting product is a 6-chloro-4,6-estradiene of the formula

wherein R is hydrogen, alkyl, tetrahydropyranyl or an acid residue. These compounds are subjected to the action of an agent furnishing positive and negative chlorine so as to form the 6,6,7-trichloro compound. The latter compound is then treated with a base. Depending on the desired character of R and the starting compound employed (in respect of R), an esterified or etherified hydroxyl group may then be subjected to hydrolysis or, if a free hydroxyl group is present, the latter group may be esterified or etherified.

Positive and negative chlorine may be obtained during the reaction from suitable chlorine-containing compounds. Positive chlorine for instance is obtained from N-chloro-acylamides or -acylimides, preferably N-chloro-acetamide or N-chloro-succinimide. However, hypochlorites may also be used, such as tert. butylhypochlorite.

Agents furnishing negative chlorine are for instance chlorides, preferably lithium chloride.

In addition it is also possible to split up elementary chlorine into positive and negative chlorine.

For instance, a steroid of the formula given above for the starting compounds may be dissolved in acetic acid and then subjected to the action of lithium chloride and

N-chlorosuccinimide in the presence of a strong anhydrous acid such as hydrochloric acid in dioxane or tetrahydrofuran. The corresponding 6,6,7-trichloro compound is then formed by chlorination of the Δ^6 -double bond. The trichloro compound is thereafter treated, preferably with an organic base, to split off hydrogen chloride. The splitting off of the hydrogen chloride is accompanied by a migration of the chlorine atom to the 4-position.

Chlorination and hydrogen chloride elimination take place under mild conditions, preferably at temperatures around room temperature.

The subsequent esterification, etherification and saponification reactions can be carried out in conventional manner.

For instance, for the purpose of esterification, a reaction may be chosen with an acid anhydride or acid halide in the presence of an acidic or basic agent or the reaction may be carried out with the desired free acid in the presence of trifluoroacetic acid anhydride.

For the purpose of the saponification, it is preferable to subject the 17-carboxylic acid esters to the action of a base, for instance an alkali hydroxide, alcoholate or alkali carbonate in the presence of water, preferably an alcoholic solution and, if desired, upon addition of a solution promoting agent.

To make the 17-tetrahydropyranylethers, the 17-hydroxy compound can be reacted with dihydropyran in the presence of an acid such as p-toluenesulfonic acid. The etherification with an alkyl residue preferably is effected with an alkyl halide in the presence of a basic condensation agent such as silver oxide.

MAKING OF THE STARTING PRODUCTS

The starting products of the above-given formula (II) may for instance be obtained as appears from the following two examples:

(A) Rac.-6-chloro-17 β -acetoxy-18-methyl-17 α -ethinyl-4,6-estradiene-3-one

Rac. 17 β -acetoxy-18-methyl-17 α -ethinyl - 4 - estrene-3-one is reacted with formic acid ethyl ester in the presence of concentrated sulfuric acid in dioxane at room temperature. The thus-obtained rac.-3-ethoxy-17 β -acetoxy-18-methyl-17 α -ethinyl-3,5-estradiene, M.P. 175-183° C., is brominated with N-bromosuccinimide in the 6-position. Hydrogen bromide is then split off from the resulting 6 β -bromo-17 β -acetoxy-18-methyl-17 α -ethinyl - 4 - estrene-3-one in dimethylformamide in the presence of lithium bromide and lithium carbonate. There is thus obtained racemic 17 β -acetoxy - 18 - methyl-17 α -ethinyl-4,6-estradiene-3-one; M.P. 167.5-172° C.

In order to introduce the chlorine atom in the 6-position, the 6 α ,7 α -epoxide is formed with m-chloroperbenzoic acid and the epoxide is then treated with hydrogen chloride in acetic acid at room temperature. The resulting rac.-6 β -chloro-7 α -hydroxy-17 β -acetoxy - 18 - methyl-17 α -ethinyl-4-estrene-3-one is converted to the 7-mesylate with methane sulfonic acid chloride in pyridine. From the 7-mesylate the rac.-6-chloro-17 β -acetoxy - 18 - methyl-17 α -ethinyl-4,6-estradiene-3-one is obtained by heating in pyridine in the presence of sodium acetate; M.P. 203-205° C.

(B) Nat.-6-chloro-17 β -acetoxy-18-methyl-17 α -ethinyl-4,6-estradiene-3-one

Nat.-17 β -acetoxy - 18 - methyl-17 α -ethinyl-4-estrene-3-one is converted to the 3-enoylethylether in the same manner as was used in Example A. By bromination and subsequent elimination of hydrogen chloride, there is obtained nat.-17 β -acetoxy-18-methyl-17 α -ethinyl-4,6-estradiene-3-one; M.P. 206-207° C. (UV: $\epsilon_{282}=26,100$).

To introduce the chlorine atom in the 6-position, the 6 α ,7 α -epoxide is formed with m-chloroperbenzoic acid.

The epoxide is then treated with hydrogen chloride in acetic acid. The thus-formed 6β -chloro- 7α -hydroxy compound, in order to introduce the Δ^6 -double bond, is then treated in the same manner as in Example A, in the first place with methanesulfonic acid chloride and subsequently with sodium acetate. There is thus obtained nat.-6-chloro- 17β -acetoxy - 18 - methyl- 17α -ethinyl-4,6-estradiene-3-one; M.P. 214-215.5° C. This compound in the ultraviolet test has an extinction of $\epsilon_{283}=22,300$.

The following examples will illustrate the making of the compounds of the invention from the identified starting products.

EXAMPLE 1

1.4 g. of rac.-6-chloro- 17β -acetoxy - 18 - methyl- 17α -ethinyl-4,6-estradiene - 3 - one was dissolved in 200 ml. 15 acetic acid and successively reacted with 7 g. of lithium chloride, 1.4 g. of N-chlorosuccinimide and 0.3 ml. dioxane saturated with hydrogen chloride gas. After a reaction time of 7 minutes at room temperature, the product is added while stirring to ice water and the formed precipitate is removed then by suction and taken up in methylene chloride. The methylene chloride phase is washed with sodium bicarbonate solution and water, dried over sodium sulfate and concentrated by evaporation to dryness in a vacuum.

The residue is dissolved in 5 ml. pyridine and permitted to stand for 16 hours at room temperature. It is thereafter taken up in ether, washed with dilute hydrochloric acid and water, dried and concentrated by evaporation to dryness in a vacuum. The residue is subjected to chromatography on silica gel and thereafter recrystallized from acetone/hexane. There is obtained 0.6 g. of rac.-4,6-dichloro- 17β -acetoxy - 18 - methyl- 17α -ethinyl-4,6-estradiene-3-one; M.P. 210-213.5° C. (decomposition).

EXAMPLE 2

Nat.-6-chloro- 17β -acetoxy - 18 - methyl - 17α - ethinyl-4,6-estradiene-3-one is reacted analogously to Example 1 and subjected to the same further treatment. There is obtained nat.-4,6-dichloro- 17β -acetoxy - 18 - methyl - 17α -ethinyl-4,6-estradiene-3-one; M.P. 230-231.5° C. UV: $\epsilon_{303}=18,100$.

EXAMPLE 3

1.9 g. of nat.-6-chloro- 17β -hydroxy-18-methyl- 17α -ethinyl-4,6-estradiene-3-one are dissolved in 300 ml. acetic acid and successively reacted with 10 g. of lithium chloride, 1.9 g. of N-chlorosuccinimide and 0.4 ml. dioxane/HCl. After a reaction time of 7 minutes at room temperature, the subsequent treatment is started and carried out as in Example 1.

The isolated product is then dissolved in 5 ml. pyridine and left standing for 16 hours at room temperature. It is then taken up in ether, washed with dilute hydrochloric acid and water, dried and concentrated by evaporation to dryness in a vacuum. The residue is subjected to chromatography on silica gel and, after recrystallization from acetone/hexane, 400 mg. of nat.-4,6-dichloro- 17β -hydroxy-18-methyl- 17α -ethinyl-4,6-estradiene-3-one are obtained; M.P. 216-216.5° C. UV: $\epsilon_{304}=16,800$.

EXAMPLE 4

1.0 g. of nat.-6-chloro- 17β -heptanoyloxy-18-methyl- 17α -ethinyl-4,6-estradiene-3-one are dissolved in 100 ml. acetic acid and reacted with 5.0 g. lithium chloride, 1 g. N-chlorosuccinimide and 0.2 ml. dioxane/HCl. After a reaction time of 7 minutes at room temperature, the following treatment is started and carried out as in Example 1. The product is subsequently treated with pyridine and then subjected to chromatography on silica gel. There are obtained 350 mg. of nat.-4,6-dichloro- 17β -heptanoyloxy-18-methyl- 17α -ethinyl-4,6-estradiene-3-one in the form of an oil. UV: $\epsilon_{303}=17,000$.

EXAMPLE 5

500 mg. of nat.-4,6-dichloro- 17β -acetoxy-18-methyl- 17α -ethinyl-4,6-estradiene-3-one are heated in 50 ml. 10 methanol with 500 mg. p-toluenesulfonic acid for 24 hours while slowly effecting distillation. The mass is then diluted with ether, washed with water and concentrated by evaporation to dryness in a vacuum. After recrystallization from acetone/hexane there is obtained nat.-4,6-dichloro- 17β -hydroxy-18-methyl- 17α -ethinyl-4,6-estradiene-3-one; M.P. 215-216° C. UV: $\epsilon_{304}=16,500$.

What is claimed is:

1. A racemic or optically active 4,6-dichloro-4,6-estradiene of the formula

wherein R is hydrogen, lower alkyl, tetrahydropyranyl or a carboxylic acid group containing up to 15 carbon atoms.

2. The estradiene of claim 1, wherein alkyl is methyl, ethyl, propyl or butyl.

3. The estradiene of claim 1, wherein the acid residue is formed of a carboxylic acid having up to 15 carbon atoms.

4. The estradiene of claim 1, which is rac.-4,6-dichloro- 17β -acetoxy-18-methyl- 17α -ethinyl-4,6-estradiene-3-one.

5. The estradiene of claim 1, which is nat.-4,6-dichloro- 17β -acetoxy-18-methyl- 17α -ethinyl-4,6-estradiene-3-one.

6. The estradiene of claim 1, which is nat.-4,6-dichloro- 17β -hydroxy-18-methyl- 17α -ethinyl-4,6-estradiene-3-one.

7. The estradiene of claim 1, which is nat.-4,6-dichloro- 17β -heptanoyloxy-18-methyl- 17α -ethinyl-4,6-estradiene-3-one.

8. The process of making the compounds of claim 1 comprising subjecting a 6-chloro-4,6-estradiene of the formula

wherein R has the meaning as given in claim 1, to the action of an agent furnishing positive and negative chlorine, thereby forming the 6,6,7-trichloro compound and then treating the trichloro compound with a base.

9. The process of claim 8 wherein the 21-OR group is an ester or ether group in the starting product and wherein in the final product is then subjected to hydrolysis of the said ester or ether group.

10. The process of claim 8 wherein the 21-OR group of the starting product is a free hydroxyl group and wherein the final product is subjected to esterification or etherification of the 21-hydroxyl group.

11. The process of claim 8, wherein as agent furnishing positive chlorine N-chlorosuccinimide or N-chloroacetamide is employed.

12. The process of claim 8, wherein as negative chlorine furnishing agent lithium chloride is employed.

13. The process of claim 8, wherein the base is an organic base.

14. The process of claim 13, wherein the base is pyridine.
